UNITED STATES PATENT OFFICE

156,083

DESIGN FOR A TUMBLER

Kemper H. Ferree, Chicago, Ill., assignor to Kraft Foods Company, Chicago, Ill., a corporation of Delaware

Application May 22, 1948, Serial No. 146,522

Term of patent 3½ years

(Cl. D36—8)

To all whom it may concern:

Be it known that I, Kemper H. Ferree, a citizen of the United States, residing at Chicago, in the county of Cook and State of Illinois, have invented a new, original, and ornamental Design for a Tumbler, of which the following is a specification, reference being had to the accompanying drawing, forming part thereof.

I claim:

The ornamental design for a tumbler, substantially as shown.

KEMPER H. FERREE.
